(57) **CLAIM**

The ornamental design for a car-wash device, as shown and described.

DESCRIPTION

FIG. 1 is a front and top perspective view of a car-wash device, showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a perspective view of the car-wash device showing in a state of use; and,
FIG. 9 is a rear view thereof.
The broken lines in the figures illustrate portions of the car-wash device that form no part of the claimed design. All other broken lines shown in FIGS. 8 and 9 are for the purpose of illustrating environmental structure and form no part of the claimed design.
